Inventor:

Ambrose H. Kite

UNITED STATES PATENT OFFICE.

AMBROSE H. KITE, OF STILLWATER, OKLAHOMA TERRITORY, ASSIGNOR OF ONE-HALF TO F. M. STALLARD, OF SAME PLACE.

POST-AUGER.

SPECIFICATION forming part of Letters Patent No. 560,267, dated May 19, 1896.

Application filed December 5, 1895. Serial No. 572,811. (No model.)

To all whom it may concern:

Be it known that I, AMBROSE H. KITE, a citizen of the United States, residing at Stillwater, in the county of Payne and Territory of Oklahoma, have invented a new and useful Post-Auger, of which the following is a specification.

My invention relates to improvements in post-augers, which in taking the core of the post-hole out in a solid piece, saves labor and time.

I have attempted to explain the mechanism of my invention in the accompanying drawings.

15 Figure 1 is a vertical section of the auger complete. Fig. 2 is a bottom view of the auger, showing outside cutting-knives and a part of the core-drum and the core-knives; also the guide-wheel that holds the auger in position while starting the hole.

20 Similar letters refer to similar parts throughout both views.

The wood handle at *a a* passes through a hollow piece which connects with pipe *c*.
25 Pipe *c* connects with piece *p p* and *p p* connects with piece *k k*, that passes down to and fastens to the core-drum *i*. The object of using gas-pipe is to give strength and prevent weight and lessen the cost of manufacture.

30 *d d* in Fig. 1 represent buttons or thumb-bolts connected with small steel rods *t t*, the ends of which are flattened out and form core-knives *i i*. (Shown in bottom section, Fig. 2.)

By turning buttons *d d* the operator will

be able to throw out the knives *e e*. Then by 35 turning the auger one-fourth around to the left the knives will occupy the position shown by dotted lines.

l l in Fig. 2 represent outside cutting-knives.

l l in Fig. 2 shows end section of core-drum. 40

h h shows the guide that holds the auger when starting.

e represents center rod or a part of the guide which stays in a stationary position while operating the auger. 45

g g in Fig. 1 is a cross-bar that slides within the core-drum and holds the rod *e* in position. Rod *e* passes up through pipe *c* as the auger goes down.

50 When the auger has been removed from the hole, the operator may by turning the buttons *d d* throw the core-knives back to their position, and thus free the auger from the dirt or core of the post-hole.

What I claim for a patent from the United 55 States for this invention is—

In an earth-auger, the combination with the inclosing cylinder and core-drum and attached cutters, the rods which extend up through the cylinder and having cutters on 60 their lower ends, and the centering-rod and attached guide-plate, substantially as set forth.

AMBROSE H. KITE.
